UNITED STATES PATENT OFFICE.

JOHN J. CURRAN, OF WEST HAVEN, CONNECTICUT.

MACHINE FOR OVERCASTING.

Application filed October 24, 1922. Serial No. 596,578.

To all whom it may concern:

Be it known that I, JOHN J. CURRAN, a citizen of the United States, residing at West Haven, in the county of New Haven and State of Connecticut, have invented a new and useful Improvement in Machines for Overcasting; and I do hereby declare the following, when taken in connection with the accompanying drawings and the characters of reference marked thereon, to be a full, clear, and exact description of the same, and which said drawings constitute part of this application, and represent, in—

Fig. 1 a view in side elevation of one form which a machine embodying my invention may assume, with a bag shown by broken lines in position to have its mouth entered into it for being overcast or sewed up by an overcast stitch.

Fig. 2 a view in end elevation of the receiver-end of the machine.

Fig. 3 a corresponding view of the delivery-end of the machine.

Fig. 4 a view of the machine on the line 4—4 of Fig. 1.

Fig. 5 a view in elevation of the helical overcasting needle.

Fig. 6 an end view thereof, looking toward its point.

Fig. 7 a corresponding view, looking toward its thread-carrying head.

Fig. 8 a view in elevation, showing a bag as overcast in the machine.

Fig. 9 a view after the ends of the twine have been manually tied to form ears at the ends of the mouth of the bag.

Fig. 10 a broken detail end view of the head of the needle.

Fig. 11 a corresponding side view thereof.

Fig. 12 a sectional view thereof on the line 12—12 of Fig. 11.

Fig. 13 a broken view in perspective of a section of a modified form that the overcasting needle may assume.

My invention relates to an improved machine for closing by overcasting the mouths of bags or sacks containing grain, meal, feed, fertilizer, sugar, potatoes, and a great variety of merchandise marketed in bags or sacks, the object being to produce a simple, convenient, durable and rapidly-operating machine constructed for closing the mouths

of bags or sacks by that form of sewing known as overcasting, which combines the security of chain-stitch sewing and is, at the same time, far more easily removed than the same, without destroying or mutilating the fabric of the bag or sack.

With these ends in view, my invention consists in a sewing machine having a helical overcasting needle of the character described and certain other details of construction as will be hereinafter described and pointed out in the claims.

In carrying out my invention, as herein shown, I employ a cylindrical helical overcasting needle 15 provided at its forward end with a point 16, and formed upon the outer face or periphery of its opposite end or head with a thread pick-up and carrying hook or equivalent device 17 turned inwardly with respect to the said point 16, and produced by a transverse undercut 18 flanked on either side by complementary thread-receiving grooves 19, respectively receiving the opposite reaches of a piece of thread or twine 20, of predetermined length, and allowing the same to lie within the diameter of the needle, so as not to obstruct the passage of the head thereof through the fabric of a bag or sack 21, it being understood that what I have herein designated as the head of my improved helical overcasting needle corresponds to the eye of an ordinary needle, in so far as the eye of a common needle is the portion thereof which carries the thread.

By locating the hook 17 upon the periphery of the head-end of the needle, it is adapted to pick up the thread without stopping the needle, which thus becomes self-threading. Such a helical needle 15, having more or less convolutions as desired, is supported and driven by a plurality of smooth or un-grooved, cylindrical parallel rolls positioned so as to confine or cage it and so as to have frictional engagement with the peripheries of its convolutions. The number of these rolls may be varied as desired, and one or more or all of them may be utilized for driving the needle. As herein shown, I employ an upper roll 22 and oppositely-located lower rolls 23 and 24. These rolls are journaled at their ends in the end-plates or uprights 25 and 26 of a machine-frame comprising also horizontal cross-pieces 27,

but the character and construction of the machine-frame is not of the essence of my present invention. The inner ends of the said rolls project through the end-plate or upright 26 and are respectively provided with pinions 28, 29 and 30, all of the same size. An idler-pinion 31, interposed between the pinion 28 and the pinion 29, provides for driving the roll 23 in the same 5 direction as the roll 22, while an idler-pinion 32, interposed between the pinion 28 and the pinion 30, provides for driving the roll 24 in the same direction as the rolls 22 and 23. The projecting end of the roll 22 also 10 carries a gear 33 meshing into and driven by a pinion 34 turning with a driving gear 35 mounted on a stud 36 carried by a bracket 37 rising between the cross-plates 27 of the machine-frame from the end- 15 plate 26.

As shown, the rolls 22, 23 and 24 are located at the three corners of a triangle and constitute, as it were, a cage for the confinement and support of the needle, 20 which they hold against lateral displacement in any direction, while it is prevented from substantial longitudinal or axial displacement by the end-plates 25 and 26 of the machine-frame. The number of rolls 25 may be varied as desired, and it is not necessary that all of them shall be utilized for driving the needle, but as many as are 30 so utilized must be rotated in the same direction.

As shown, provision is made for adjusting the roll 24 by providing its ends with bushings 38, which have limited movement in slightly elongated slots 39 in the upright frame-pieces 25 and 26, mounting adjusting-screws 40 impinging against the said bushings for adjusting the roll with reference to the helical needle, whereby the tension imposed upon the outer peripheral surfaces of the convolutions thereof may be 45 varied as desired.

As herein shown, also, I employ a guard-roll 41 journaled at its ends in the inner ends of two heavy, complementary, pivotal mounting-arms 42 hung upon studs 43 in the frame-pieces 25 and 26 and provided at their outer ends with set-screws 44 having locking-nuts 45 and engaging with abutments 46 offsetting from the said frame-pieces 25 and 26. The said guard-roll 41 50 is located substantially below the needle, in close proximity thereto, but not in engagement therewith, on that side of the vertical longitudinal center of the machine toward which the bottom of the needle rotates, as shown in Fig. 4. The function of this roll 55 is to guard against the undue displacement of the mouth of the bag, in passing through the machine, due to the drag of the needle and thread. For this purpose the guard-roll 60 65 41 is turned in the opposite direction from

the rolls 22, 23 and 24, by means of a pinion 47 mounted upon its projecting rear end and meshing into the pinion 29 of the roll 23. It is intended that the peripheral speed of the guard-roll 41 shall be at 70 least equal to the peripheral speed of the needle. It is not, however, essential to drive the guard-roll, as a fixed guard would serve the same purpose, though perhaps less efficiently. 75

By preference and as shown, the rolls 22, 23 and 24 are formed at their ends with concaved annular guard-flanges 48 to assist in preventing the axial displacement of the needle. 80

To provide a passage through the machine for the mouth of the bag or sack to be overcast, the end-plates 25 and 26 are respectively provided with oppositely-placed, vertical bag clearance openings 49 and 50, 85 preferably extending upward above the axis of the needle and substantially centrally located between the rolls 23 and 24. The guard-flanges 48 aforesaid, adjacent to the bag-clearance opening 49, prevent the entrance thereto of the pointed end of the helical needle in case of its bodily axial displacement in the direction of the said opening. They also resist any tendency which may exist for the point of the needle to 90 enter the said opening, in which case the needle would be deformed or broken and the machine stopped. 95

In the use of my improved machine, the operator or sewer preferably takes a previously cut piece of thread or twine 20 of suitable length and engages it near one of its ends with the hook 17, on the head end of the rotating needle, as the same passes the clearance-opening 50 in the end-plate 26. 105 The twine having been thus engaged with the needle, the sewer lets go of it and guides the mouth of the bag into the clearance-opening 49, in the end-plate 25, and, therefore, into the path of the point of the needle, 110 which pierces the bag at regularly spaced intervals, corresponding to the spacing of the convolutions, as the mouth of the bag is moved from front to rear through the machine. After all of the convolutions of 115 the needle have passed through the bag, the needle begins to draw the twine through the openings already pierced in the bag, in the manner of overcasting in hand sewing. The piece of twine 20 is adapted in length not only to close the mouth of the bag, but to leave two fastening ends 51: 51, as shown in Fig. 8. These are manually hitched around the corners of the bag, as shown in Fig. 9, producing the ears 52: 52 120 125 by which the bag 21 is handled.

I am thus, by my improved overcasting machine, enabled to simulate hand-sewn overcast bags, which are greatly preferred by the consumer to ordinary machine-sewn 130

bags, inasmuch as overcasting is not only far easier to remove than chain-stitching, but also may be removed without any mutilation of the fabric of the bag or sack.

In Fig. 13 I have shown a needle of triangular, rather than round, cross-section, such a needle being also adapted to be peripherally driven.

I would have it understood that I do not limit myself to the particular construction shown and described herein, as the details thereof may be changed in many respects without departing from my invention, which is characterized by the employment of a helical overcasting needle formed at one end with a point and at its opposite end with a peripheral thread pick-up and carrying hook in its butt or head, and suitably supported and driven together with means at its pointed end for preventing the same from entering the bag-clearance opening adjacent thereto. I have described the manual threading of the needle by previously cut lengths of twine, but, of course, the twine might be cut off from a source of supply, after the overcasting operation, or the twine might be automatically fed and severed, all without departing from my invention. While my improved machine was primarily designed for overcoating bags, sacks, and the like, it might be used for other overcasting purposes.

I claim:

1. In a machine for overcasting bags, the combination with a frame provided with bag-clearance openings, of a plurality of rolls mounted in the said frame, a helical overcasting needle pointed at one end and provided at its opposite end with a peripheral thread pick-up-and-carrying hook, interposed between the said rolls and driven by one of them, and means located adjacent to the pointed end of the needle for preventing the same from entering the bag-clearance opening adjacent thereto, the said opening extending inward toward the axis of the needle, beyond the path described by the point thereof.

2. In a machine for overcasting bags, the combination with a frame provided with bag-clearance openings, of a plurality of ungrooved rolls mounted in the said frame, a helical overcasting needle pointed at one end and provided at its opposite end with a peripheral thread pick-up-and-carrying hook, interposed between the said rolls and driven by one of them, and means located adjacent to the pointed end of the needle for preventing the same from entering the bag-clearance opening adjacent thereto, the said opening extending inward toward the axis of the needle beyond the path described by the point thereof.

3. In a machine for overcasting bags, the combination with a frame provided with

bag-clearance openings, of a plurality of ungrooved cylindrical rolls mounted in the said frame, a cylindrical helical overcasting needle pointed at one end and provided at its opposite end with a peripheral thread pick-up-and-carrying hook, interposed between the said rolls and driven by one of them, and means located adjacent to the pointed end of the needle for preventing the same from entering the bag-clearance opening adjacent thereto, the said opening extending inward toward the axis of the needle beyond the path described by the point thereof.

4. In a machine for overcasting bags, the combination with a frame provided with bag-clearance openings, of a plurality of ungrooved rolls mounted in the said frame, a helical overcasting needle pointed at one end and provided at its opposite end with a peripheral thread pick-up-and-carrying hook, interposed between the rolls and driven by one of them, and a flange located upon one of the rolls adjacent to the pointed end of the needle for preventing the same from entering the bag-clearance opening adjacent thereto, the said opening extending inward toward the axis of the needle, beyond the path described by the point thereof.

5. In a machine for overcasting bags, the combination with a frame provided with two bag-clearance openings, of a plurality of ungrooved cylindrical rolls mounted in the said frame, a cylindrical helical overcasting needle pointed at one end and provided at its opposite end with a peripheral thread pick-up-and-carrying hook, interposed between the said rolls and driven by one of them, and means located adjacent to the pointed end of the needle for preventing the same from entering the bag-clearance opening adjacent thereto, the said opening extending inward toward the axis of the needle, beyond the path described by the point thereof.

6. In a machine for overcasting bags, the combination with a frame provided with two bag-clearance openings, of a plurality of ungrooved cylindrical rolls mounted in the frame, a cylindrical helical overcasting needle pointed at one end and provided at its opposite end with a peripheral thread pick-up-and-carrying hook, interposed between the said rolls and driven by one of them, and flanges located on the rolls adjacent to the respective bag-clearance openings for preventing the axial displacement of the needle.

7. In a machine for overcasting bags, the combination with a frame having two frame-plates respectively provided with aligned bag-clearance openings, of a plurality of ungrooved cylindrical rolls mounted in the said frame, a cylindrical helical over-

casting needle pointed at one end and provided at its opposite end with a peripheral thread pick-up-and-carrying hook, interposed between the said rolls and driven by one of them, and means located adjacent to the pointed end of the needle for preventing the same from entering the bag-clearance opening adjacent thereto, the said opening extending inward toward the axis

of the needle beyond the path described by 10 the point thereof.

In testimony whereof, I have signed this specification in the presence of two subscribing witnesses.

JOHN J. CURRAN.
